Primary Examiner — Mojtaba Tehrani*(74) Attorney, Agent, or Firm* — Bold IP, PLLC; Houda El-Jarrah(57) **CLAIM**

The ornamental design for a scent dispersing trolling lure, as shown and as described.

DESCRIPTION

FIG. 1 is a top perspective view of a scent dispersing trolling lure showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a top view showing an open lid for the scent dispersing trolling lure.

The broken lines included in the Figures above show environmental structure and form no part of the claimed design.

1 Claim, 7 Drawing Sheets(56)
